UNITED STATES PATENT OFFICE.

OTTO D. HOLLE, OF BREMEN, KANSAS.

WRENCH.

Application filed July 25, 1923. Serial No. 653,768.

To all whom it may concern:

Be it known that I, OTTO D. HOLLE, a citizen of the United States, residing at Bremen, in the county of Marshall and 5 State of Kansas, have invented new and useful Improvements in Wrenches, of which the following is a specification.

This invention relates to certain new and 10 useful improvements in wrenches, and has particular reference to that class of tools known as socket wrenches.

Primarily the object of the invention is 15 to provide a wrench having its socket portion adapted for the reception of a handle and the positioning of means within said socket portion whereby the wrench may be used as an ordinary wrench; as a ratchet wrench; and having additional means so 20 the tool is reversible when used as a ratchet wrench.

A further object is the provision of a wrench having various size sockets adapted 25 for fitting hexagonal, square, or other shaped heads of a bolt.

With the above general objects in view 30 and others that will appear as the nature of the invention is better understood, the same consists of the novel form, combination and arrangement of parts hereinafter more fully described, shown in the accompanying drawings and claimed.

In the drawings, wherein like reference 35 characters designate corresponding parts through the several views:

Figure 1 is a side elevation of the wrench. Fig. 2 is an enlarged sectional view of 40 the socket portion, illustrating the connection between the handle and said socket portion.

Fig. 3 is an enlarged cross-section on the line 3—3 of Fig. 2, the socket and handle in this instance being locked together.

Fig. 4 is a similar view but showing the 45 position of certain pawls when the tool is used as a ratchet wrench.

Referring more in detail to the accompanying drawings, there is illustrated the handle of the wrench 5 which is preferably L-shaped, and having its extremities cut to 50 form elongated teeth, as indicated at 6 and 7. My purpose in having these extremities similarly cut is to make said handle readily interchangeable and adapt the same to suit situations where accessibility and other conditions must be taken into consideration. 55 It will, of course, be understood that shape

of said handle is of minor consideration so long as my means of constructing the connecting extremities is carefully adhered to. Each end of said handle 5, just rearwardly 60 of the teeth 6 and 7, is provided with an aperture 9 for the reception of a spring-pressed friction ball 10, which serves to secure the handle to the socket 8, as will be more fully pointed out hereinafter. The 65 spring-pressed ball 10 is backed by a plug 11 seating within said aperture 9.

The socket 8 has its lower portion hollowed out, as indicated at 8^a, and may be made hexagonal, square, or oval, and of various sizes, so that no standard size bolt or nut will be without the range of the sockets. The shank 13 of said socket is provided with an axial bore 14, two diametrically opposed slots 15 and 15^a, for the reception of pawls 16 and 16^a which latter are pivoted to said shank as indicated at 17. Further, a substantially semi-circular groove 18 is cut between the said slots 15 and 15^a, on the outer face of said shank, for the reception of a spring 19.

A ring 20 encircles said shank portion and is cut away as indicated at 21, (Fig. 1) exposing the slots 15 and 15^a, and is further provided with inwardly directed lugs 85 22 and 22^a, said lugs co-acting with the pawls hereinbefore referred to in a manner to be hereinafter pointed out.

Figures 3 and 4 of the drawings clearly depict the relation of the associated parts 90 described above.

The axial bore 14 is provided with an annular groove 24 which receives the friction ball 10. It will thus be seen that when the extremities of the handle are inserted 95 in the bore of the socket, the friction ball backs into the aperture 9 until it is opposite the groove 24, whereupon the ball under the influence of its spring snaps into said groove and serves as sufficient connection between the handle and its socket. The sharp outward pull releases the handle. It is apparent that when the tool is used as a ratchet wrench the partial revolution of the handle is not attended by the usual wear 105 and tear, since my construction provides a substantially ball bearing between said handle and socket.

As pointed out in the brief description the 110 said handle and socket are shown locked together in Fig. 3. Considering now this view, it is apparent that when the ring 20 is turned

2
to the left the lug 22 cooperates with the pawl 16 drawing the same out of contact with the toothed end of the handle, as shown in Fig. 4. In this position the tool becomes 5 a ratchet wrench, thus by moving the handle back and forth it enables one to work in cramped quarters. Conversely when the ring 20 is turned to the right said lug 22 strikes the side extension 16^b of the pawl 10 and throws the latter back into engagement with the toothed end of the handle. During this latter operation the lug 22^a may be made 15 to co-act with the pawl 16^a by turning the ring 20 still further to the right, whereupon the said pawl is released from the toothed end of the handle, thereby making the tool reversible.

The ends of the spring press against the pawls and urge them into engagement with 20 the adjacent piece. This spring is held in place by the ring 20.

It will be noted that when both pawls are 25 engaged, as indicated in Fig. 3, the tool is operated as an ordinary wrench, that is, the handle and the socket are locked together.

It is, of course, to be understood that the invention may be constructed in other manners and the parts associated in different relations and, therefore, I do not desire to be 30 limited in any manner except as set forth in the claims hereunto appended.

I claim:

1. A tool of the character described comprising a socket portion having a bored 35 shank, said shank having diametrically opposed slots and a groove extending substantially half-way around said shank, a spring in said groove, a handle adapted to enter said shank and having its extremities provided with elongated teeth, pawls associated 40 with said socket portion and entering said slots and means for operating said pawls for

the purpose of either locking the handle to the socket portion or operating so the tool may be used as a ratchet. 45

2. A tool of the character described comprising a socket portion having a bored shank, said shank having diametrically opposed slots and a groove extending substantially half-way around said shank between 50 said slots, a spring seating within said groove, a handle adapted to enter said shank and having its extremities provided with elongated teeth, pawls associated with said socket portion and entering said slots and a 55 ring encircling said shank provided with inwardly directed lugs that cooperate with said pawls for the purpose of either locking the handle to the socket portion or operating so the tool may be used as a ratchet. 60

3. A wrench comprising a handle, said handle having elongated teeth cut in both ends and provided with a transverse aperture rearward of said teeth, a spring-pressed ball positioned in said aperture, a hollow 65 socket provided with a shank portion having an axial bore, said bore having an annular groove for the reception of said spring-pressed ball, said shank being further provided with diametrically opposed horizontal 70 slots and a groove extending substantially half-way around said shank between said slots, a spring seating within said groove, pawls pivoted within the groove of said shank and of sufficient length to enter said 75 slots and engage said teeth of said handle, said pawls having side extensions and a ring encircling said shank and having inwardly directed lugs that cooperate with the pawls to seat them within the teeth of said handle 80 and to cooperate with said side extensions to remove the same.

In testimony whereof I affix my signature.
OTTO D. HOLLE.
